FIG. 1.

FIG. 2.

FIG. 3.

FIG. 4.

FIG. 5.

FIG. 6.

Inventor
Henry E. Keyes,
by Hubert W. Jenner,
Attorney.

UNITED STATES PATENT OFFICE.

HENRY E. KEYES, OF MOUNT HOLLY, NEW JERSEY.

HAMMER.

Application filed May 17, 1927. Serial No. 192,034.

This invention relates to hammers having removable plugs in their faces to adapt them to be used for different purposes; and it consists in the novel construction and combination of the parts hereinafter fully described and claimed.

In the drawings, Figure 1 is a side view of a hammer head constructed according to this invention. Fig. 2 is a section through 10 the hammer head, taken on the line 2—2 in Fig. 1. Fig. 3 is an end view of the hammer head with the raw-hide plug and metal abutment washer removed. Fig. 4 is a section through the raw-hide plug showing a 15 modification. Fig. 5 is a section through a metal plug before being inserted in the socket, and also showing a modification. Fig. 6 is a section through a plug socket, taken on the line 6—6 in Fig. 1, and showing 20 the metal abutment washer in place.

The hammer is provided with any approved handle, and preferably a wooden handle 10 has one end portion secured in a hole 12 in the hammer head 14. The hammer head preferably has a similar socket or enlargement 15 at each end, but it may have only one of these sockets, and the other end may be any approved form of striking face or end. When two sockets 15 are provided, 30 one of them is preferably provided with a raw-hide plug 16, and the other with a metal plug 17. Each plug is removable and renewable.

The non-metallic plug 16 may be formed 35 of fiber, raw-hide, or other similar material. The metal plug 17 may be formed of copper, brass, aluminum, steel, or other similar material.

Each socket 15 is cylindrical, and is of the 40 same diameter at each end. Each socket is provided with ejector slots 18 in its sides. The inner ends of these slots extend below the bottom 19 of the socket, and form passages 18' in the bottom, which passages are 45 arranged crosswise of each other. The outer ends of the slots 18 may extend to the outer ends of the socket if desired, but they preferably are formed as shown, so that the metal is not cut away at the outer end of the 50 socket.

The sockets are larger in external diameter than the width of the head between them, and form shoulders 31 as shown in Fig. 2, and the head is provided with a circular recess 20 on each side. When the head is

formed in this way it is relatively light, and well balanced, and is very strong at the sides of the hole in which the handle is secured. The bottoms of the recesses 20 form convenient places for advertising labels or monograms.

The metal plug 17 has a dished inner end 22, and when the plug is driven into its socket the lip 23 at its periphery is expanded into a circumferential groove 24 in the bottom of the socket. In the modification shown in Fig. 5 the metal plug 17 has a hemispherical striking face 25, and it has a shoulder 28 which bears on the end of the socket, and its lip 23 is shown unexpanded 60 and ready for insertion in the socket.

The socket 15 for a raw-hide plug may also have a circumferential groove 24, if desired, to enable a metal plug to be substituted for a raw-hide plug. When used only 70 for raw-hide the groove 24 can be left out, as raw-hide cannot be expanded into a circumferential groove like metal.

When the socket is formed to receive a raw-hide plug, recesses 26 are formed in the 80 bottom of the socket, co-axial with the socket, and at the points of intersection of the ejector slots 18. A circular washer or abutment plate 27 is fitted into these recesses to form an abutment for the end of the central part of the plug, so as to prevent its 85 inner end from being hammered into the passages 20. In order to secure the non-metallic plug in its socket, two holes 30 are formed in the bottom of the socket diagonally of its axis.

These holes 30 extend between the bottom of the socket and the shoulder 31 formed externally around and beyond its bottom, and they converge towards each other. Fastening screws 32 are 90 inserted in the holes 30, and are screwed tightly into the raw-hide plug to secure it in place. These screws 32 are arranged at an acute angle to each other at diametrically opposite points of the hammer head, so that 95 they pull the plug tightly against the abutment plate 27. These screws pass through the said holes and through the arcuate spaces formed between the periphery of the abutment plate and the side wall of the socket 15. 100 These holes 30 may be used as ejector holes for the plug when the screws are removed. Any suitable drift is used which can be inserted in the ejector slots or holes. The socket for the metal plug preferably has 110

these holes 30, to enable it to have a raw-hide plug substituted for the metal plug, if desired.

In the modification of the raw-hide plug 5 16 shown in Fig. 4, the plug is provided with a recess 34 in its end, and the abutment washer 27 is sunk into this recess. When thus sunk into a recess, the recesses 26 are 10 not required, but the plug and the bottom of the socket may each have washers fitted into them, the precise arrangement being immaterial so long as a sufficient abutment is provided for the raw-hide plug.

When a hammer head is provided with removable and interchangeable plugs in this 15 manner it is adapted to a great variety of uses, and the plugs are not liable to become accidentally detached and lost.

What I claim is:

20 1. A hammer head provided with a socket having ejector slots in its side wall and bottom and having also holes for fastening screws in its bottom arranged one on each side of the socket and at an acute angle to each other, an abutment plate arranged over the inner end portions of the ejector slots in the bottom of the socket leaving spaces 25 between the abutment plate and the side wall

of the socket, a non-metallic plug inserted in the socket, and fastening screws passing through the said holes and spaces and securing the plug tightly against the abutment plate.

2. A hammer head as set forth in claim 1, and having a recess formed in the bottom of the socket for the reception of the said abutment plate.

3. A hammer head as set forth in claim 1, and having a recess formed in the bottom of the socket for the reception of the said abutment plate, the said plug having also a recess in its inner end, and an abutment plate inserted in the recess in the plug and arranged to bear against the abutment plate in the bottom of the socket.

4. A hammer head as set forth in claim 1, the said socket forming an externally projecting shoulder on each side of the handle portion of the head, and the said screws having heads which bear on the shoulders without projecting laterally beyond the periphery of the socket.

In testimony wherof I have affixed my signature.

HENRY E. KEYES.
